WEB ROLL CONTROLLING MECHANISM
FOR PRINTING MACHINESHarry V. Ball, Concord, Mass., assignor to Irving
Trust Company, permanent trustee for R.
Hoe & Co., Inc., New York, N. Y., a corpora-
tion of New York

Application December 9, 1933, Serial No. 701,618

22 Claims. (Cl. 242—75)

This invention relates to braking devices for controlling the unwinding of web rolls used with printing machines and more particularly to an improved means for applying a pressure or braking action to the peripheral surface of a web roll along with a means to automatically vary said pressure according to variations in tension in the running web.

In feeding the web to a printing machine, it is desirable that the web be fed under tension to produce good printing and it is also desirable to vary the braking action under varying conditions, i. e., an increased braking action should be applied to the web roll when slack or a break occurs in the web and a decreased braking action should be applied to the web roll when the tension of the running web is increased.

Various methods of control have been used for this purpose, therefore, the present invention is intended as an improvement over the known methods and has for its particular object, the provision of means for varying the pressure applied to the peripheral surface of a web roll by the movement of a weight which movement is controlled by the axial movement of a floating web guide roller.

Generally speaking, this invention comprises an endless driven belt which is adapted to engage and apply a variable pressure to the peripheral surface of a web roll, said pressure being varied to correspond with varying positions of a floating web guide roller. A means is employed which transfers the movement of said web guide roller to a slideable counter-weight and the movement of the counter-weight is used to rock a frame which carries the endless belt, said rocking movement tending to increase or decrease the pressure of the belt upon the web roll.

With this and other objects not specifically referred to in view, the invention consists in certain novel parts, arrangements and combinations which will be fully described in connection with the accompanying drawings and the novel features pointed out in the claims hereunto annexed.

In the drawings, which show a preferred embodiment of the invention:

Figure 1 is a side elevation of a web roll control mechanism embodying the improvements of the present invention;

Figure 2 is a sectional view taken on the line and in the direction of the arrow 2 of Figure 1; Figure 3 is a plan view of the parts shown in Figure 1, taken in the direction of the arrow 3; and

Figures 4, 5 and 6 are detail end sections with parts broken away, taken in the direction of the arrows 4, 5 and 6, on Figure 1, respectively.

Referring to Figure 1, the reference character 11 indicates a portion of the machine frame upon which the various parts embodying this invention are mounted.

A web roll 12 is supported in a well known manner upon arms, one of which is indicated at 13 and which form a part of a rotatable support 10 having another pair of oppositely disposed arms similar to the arms 13 upon which a spare roll (not shown) is similarly supported.

An endless belt 14 is mounted upon suitable rollers 15, which rollers are carried by a frame 16 comprising a pair of arms 17 keyed to a rock shaft 18 and joined together by means of cross bars 19. Said rock shaft is supported in bearings 20 on the bracket 21, which brackets are secured to the machine frame 11, and has a 20 weight supporting member 22 secured at the one end thereof. The belt 14 is adapted to engage the peripheral surface of the web roll, and, as indicated in Figure 1, will have a greater portion in contact with the web roll when the roll is full 25 and the diameter is largest, as indicated by the full lines, and a very limited portion in contact with the web roll when the web is unwound as indicated by the dotted line position.

A drive is provided for the belt 14 which comprises a gear 23, secured to one roller 15 positioned on the rock shaft 18 in free running relation therewith as indicated in Figure 4 and intermediate gears 24 and 24', secured to a shaft 25, one of which gears 24', is driven by means 30 of the spur and bevel gear drive comprising gears 26 and 26', from any suitable driving shaft 27 on the machine. Said drive is preferably arranged to drive the belt 14 at a speed slightly 40 slower than the speed of the running web so as to provide a slight drag on the web roll.

It will be observed that the belt 14 would develop considerable slack in moving from the full line position to the position indicated in dotted lines. To take up said slack, a compensating device is provided which comprises a compensating roller 28, mounted on a shaft 29, and carried by arms 31, said arms being secured to a shaft 32 which is pivotally mounted in bearings 33 formed on the roller frame 16. A short lever 34 is secured to one end of the shaft 32 and has a rod 35 projecting from the end thereof, which rod is adapted to have a weight 36 adjustably mounted in an unbalanced position thereon so as to cause the compensating roller arms 31 and roller 28, 50 55

to be rocked with the shaft 32 and to thereby retain the compensating roller 28 in constant contact with the belt 14, to take up whatever slack there is. An idler roller 37, mounted on the compensating roller shaft 32, will rest in a non-operative position when the belt is in the position shown in full lines and acts as a guide roller when the compensating roller moves to the dotted line position.

10 The weight supporting member 22 comprises an arm 38 secured to the end of the rock shaft 18 and has two upwardly disposed lugs 39 which support a rod 41. A weight 42 is slidably mounted on the rod 41.

15 After mounting a web roll on its supporting arm 13, the web is led over stationary guide rollers 43, 44, then over a floating roller 45. The first named roller 43 is mounted on a shaft 46, which is supported by the brackets 21, and the 20 other roller 44 is mounted on a shaft 47 supported by brackets 50 on the machine frame 11.

25 The floating roller 45 is mounted in bearings 48, shown clearly in Figures 1, 3 and 6, both of which bearings are slidably mounted within guideways 22 or housings 49, secured to the frames 11. Each bearing member is provided with raised runner portions 51 which are adapted to slide in grooves 51a formed in the housings 49.

30 Two sprocket gears 52 are mounted on stud shafts 53—53 supported in bearings 54, which bearings are secured to the frame 11. Another pair of sprocket gears 55, opposite the first named sprocket gears 52, are supported on a shaft 56 which shaft is mounted at the ends of two arms 35 57—57 depending from a shaft 58, the latter being supported in the side frames 11. Sprocket chains 59 engage one pair of each of the said sprocket gears 52 and 55 and also have interposed between two ends thereof, the aforesaid floating 40 roller bearings 48. As indicated in the drawings, each sprocket chain is split and the free ends thereof are secured to ears 61 on the floating roller bearings 48 (see Figures 1 and 3).

45 It will be observed that by means of the above described assembly, the axial movement of the floating roller and the movement of each of said chains will be equalized.

An arm 62, pivotally secured to the side frame 11, is secured to one end of the sprocket shaft 50 58 and has an extended end 63 interposed between two set screws 64, mounted in lugs 65 projecting from the frame 11, which are adapted to be adjusted to change the position of the said arm to rock the depending shaft supporting arms 55 57, and thereby take up slack in the sprocket chains 59.

A block 66 is adjustably fastened to each of the sprocket chains 59 in any suitable manner, such as, by securing same with screws 67, and a rod 68 is connected to one of said blocks and extends through the other as shown in Figures 2 and 3. A connecting link 69 is pivotally fastened to the extended end of said rod 68 at 71 and to the slidable weight 42 at 72.

65 A novel form of biasing means is provided to normally pull the floating roller against a loop in the running web to provide tension for same, and is arranged to produce an increase in the pull on said roller as the loop is dissipated. Said 70 arrangement comprises a conical pulley 74 having a spiral groove 75 in the surface thereof and a cable 76 fixed to the smaller end of same which is adapted to be wound upon said grooved surface and has a weight 77 secured to its opposite 75 end.

In the drawings, the parts are shown in the position they assume when there is a minimum degree of tension on the web and the maximum braking action is being applied to the web roll. This frequently occurs when the machine is decelerated rapidly and there is a tendency for the roll to run ahead due to its momentum. Under ordinary running conditions the roller 45 and the weight 42 occupy positions at approximately the mid points of their ranges of travel.

5

10

It will be observed from the foregoing that the web tension is properly adjusted under all of the varying conditions to which the running web is subjected. For an example, let us assume that a looseness occurs in the web. Immediately the 15 floating roller 45 will be moved toward the left as viewed in Figure 1, thereby causing the lower portion of the chain to be moved toward the right. The link 69 is moved by the movement of the lower chain portion and will drive the slidable 20 weight 42 along the rod 41, toward the right lug 39 on the arm 38 and thus reduce the effectiveness of the weight and allowing the belt carrying frame to swing downward. This will produce a greater 25 braking pressure on the web roll and an increased tension upon the web.

15

A further example includes a condition wherein the tension on the running web becomes tightened, which if permitted to continue would result in a break in the web. The tension is immediately relieved, however, due to the movement of the floating roller 45 which will tend to move toward the right and by its movement cause the lower portion of the chain 59 and the weight 42 joined thereto, to move toward the left and will 35 rock the weight supporting member 22, and the rock shaft 18 counter-clockwise to raise the belt carrying frame and thereby decrease the tension of the belt 14 upon the web roll.

30

The braking action of the belts on the web roll 40 is thus controlled in a simple and efficient manner without involving any complicated mechanism.

35

While the invention has been shown and described in its preferred form, it will be understood 45 that certain changes and variations may be made in the specific structure provided for carrying out the invention, without, however, departing from the spirit of the invention as defined in the appended claims.

50

What I claim is:

1. Web tensioning mechanism for controlling the web feed to a printing machine, comprising an endless belt engaging the peripheral surface 55 of a web roll, a pivotally supported frame having pulleys thereon to support said endless belt, driving connections between one of said pulleys and the machine, and a slidable weight adapted to be moved to rock said belt supporting frame and vary the pressure of said belt upon the web roll.

55

2. Web tensioning mechanism for controlling the web feed to a printing machine, comprising an endless belt engaging the peripheral surface 60 of a web roll, a pivotally supported frame having pulleys thereon to support said endless belt, driving connections between one of said pulleys and the machine, means movable with said belt supporting frame having a weight slidable thereon, and means to move said weight in response to variation in the tension of the running web to rock said belt supporting frame and vary the pressure of said belt upon the web roll.

65

3. Web tensioning mechanism for controlling 70 the web feed to a printing machine, comprising an

70

75

5 endless belt engaging the peripheral surface of a web roll, a pivotally supported frame having pulleys thereon to support said endless belt, driving connections between one of said pulleys and the machine, a bracket movable with the belt supporting frame, a weight slidably movable upon a rod supported by said bracket, and means to move said weight in response to variation in the tension of the running web to rock said belt supporting frame and vary the pressure of said belt upon the web roll.

10 4. Web tensioning mechanism for controlling the web feed to a printing machine, comprising an endless belt engaging the peripheral surface of a web roll, a pivotally supported frame having pulleys thereon to support said endless belt, driving connections between one of said pulleys and the machine, a slidably weight cooperating with said belt supporting frame, a web guide roller adapted to change its axial position according to variations in web tension, and means connecting said roller with the slidable weight whereby the belt supporting frame is rocked and the belt pressure upon the web roll is varied according to the 25 axis movement of the said web guide roll.

20 5. Web tensioning mechanism for controlling the web feed to a printing machine, comprising an endless belt engaging the peripheral surface of a web roll, a rotatable frame having rollers thereon to support said belt, means for driving said belt, a floating web guide roller having its ends mounted in movable bearings, and variable leverage connecting means operated by the movement 30 of said movable bearings to rock the rotatable frame and vary the pressure of the belt on the web roll according to variations in tension of the web on the floating guide roller.

35 6. Web tensioning mechanism for controlling the web feed to a printing machine, comprising an endless belt engaging the peripheral surface of a web roll, a rotatable frame having rollers thereon to support said belt, means for driving said belt, a web guide roller biased to maintain tension on the web and having its ends mounted in 45 movable bearings, and a variable leverage connection between said movable bearings and rotatable frame, whereby said rotatable frame is rocked to vary the pressure of the belt upon the web roll according to variations in tension of the web on the floating guide roller.

50 7. Web tensioning mechanism for controlling the web feed to a printing machine, comprising an endless belt engaging the peripheral surface of a web roll, a rotatable frame having rollers thereon to support said belt, means for driving said belt, a weight cooperating with said rotatable frame to vary the radial position of the frame as the weight is moved, a web guide roller biased to maintain tension on the web, bearings for the 55 roller, guideways to receive said bearings, and means actuated by the movement of said bearings in said guideways to vary the position of the weight, whereby the pressure of the belt upon the web roll is varied as the position of the web 60 guide roll is varied.

65 8. Web tensioning mechanism for controlling the web feed to a printing machine, comprising an endless belt engaging the peripheral surface of a web roll, a rotatable frame having rollers thereon to support said belt, means for driving said belt, a weight cooperating with said rotatable frame to vary the radial position of the frame as the weight is moved, a web guide roller biased to maintain tension on the web, bearings, guideways to receive said bearings, chains connected in

driving relation with the guide roller bearings to equalize the movement thereof and a rod connecting one of said chains with said weight, whereby any movement of said latter chain will cause the weight to move and rock the rotatable 5 frame, to vary the belt pressure upon the web roll.

9. Web tensioning mechanism for controlling the web feed to a printing machine, comprising a means for applying a braking action to a web supply roll, a web guide roller, bearings for said roller movable within guideways provided therefor, means for causing the guide roller to apply a tension to the running web, means connecting one of said guide roller bearings with the means 10 for applying a braking action to the web supply roll, and a movable weight cooperating with said connecting means movable in response to the movement of the floating guide roller and varying in effectiveness when so moved, to vary the 15 pressure of the brake applying means on the web supply roll.

10. Web tensioning mechanism for controlling the web feed to a printing machine, comprising a means for applying a braking action to a web 25 supply roll, a floating web guide roller and a means to apply a varying tension upon the web guide roller comprising a spirally grooved conical pulley having a cable secured at the reduced end thereof and a weight at the opposite end of said 30 cable, and means actuated by the movement of the floating roller to vary the tension on the web supply roll.

11. Web tensioning mechanism for controlling the web feed to a printing machine, comprising 35 an endless belt engaging the peripheral surfaces of a web roll, a pivotally supported frame having pulleys thereon to support said endless belt, a compensating roller member to take up slack in the belt as the diameter of the web supply roll 40 decreases, driving connections between one of the belt pulleys and the machine, a web guide roller, bearings for said roller slidably mounted upon guideways, means for providing a tension on the web guide roller, and means for rocking said belt 45 supporting frame through the movement of the web guide roller to vary the pressure of the belts upon the web supply roll.

12. Web tensioning mechanism for controlling the web feed to a printing machine, comprising 50 an endless belt engaging the peripheral surface of a web roll, a pivotally supported frame having pulleys thereon to support said endless belt, a compensating roller member to take up slack in the belt as the diameter of the web supply roll 55 decreases, driving connections between one of the belt pulleys and the machine, a bracket movable with the pivotally supported frame, a weight slidably upon a rod supported by said bracket, a web guide roller, bearings for said roller slidably 60 mounted upon guideways, means for providing a tension on the web guide roller and a member connecting said guide roller bearings with the said weight, whereby the pressure of the belt upon the web supply roll is varied.

65 13. Web tensioning mechanism for controlling the web feed to a printing machine, comprising an endless belt supported on rollers and engaging the peripheral surface of a web supply roll, rocker arms secured to a rock shaft and adapted 70 to support said belt rollers, a driving connection between one of said belt rollers and the machine, a bracket secured to another portion of said rock shaft having a counter-weight slidably mounted thereon, a tensioned floating web 75

- roller, and means connected therewith to vary the position of the said counter-weight and thereby rock the rock shaft and rocker arms thereon to vary the pressure of the belt upon the web supply roll.
14. Web tensioning mechanism for controlling the web feed to a printing machine, comprising an endless belt supported on rollers and engaging the peripheral surface of a web supply roll, rocker arms secured to a rock shaft and adapted to support said belt rollers, a driving connection between one of said belt rollers and the machine, a bracket secured to another portion of said rock shaft having a counter-weight slidably mounted thereon, a tensioned floating web guide roller, bearings for said floating web guide roller slidably mounted in guideways secured to the machine, and a connecting means between said floating web guide roller bearing and counter-weight to move said counter-weight when the said floating web guide roller bearing is moved and thereby rock the rock shaft and rocker arms thereon to vary the tension of the belt upon the web supply roll.
15. Web tensioning mechanism for controlling the web feed to a printing machine, comprising an endless belt supported on rollers and engaging the peripheral surface of a web supply roll, rocker arms secured to a rock shaft and adapted to support said belt rollers, a driving connection between one of said belt rollers and the machine, a bracket secured to another portion of said rock shaft having a counterweight slidably mounted thereon, a tensioned floating web guide roller, bearings for said floating web guide roller slidably mounted in guideways secured to the machine, equalizing means secured to each floating web guide roller bearing to provide an equalized sliding movement for each of said bearings and a link connected to said counter-weight and equalizing means to move said counter-weight a distance corresponding to the movement of the floating web guide roller bearings, whereby the rock shaft and rocker arms thereon are rocked to vary the pressure of the belt upon the web supply roll.
16. Web tensioning mechanism for controlling the web feed to a printing machine, comprising an endless belt support on rollers and engaging the peripheral surface of a web supply roll, rocker arms secured to a rock shaft and adapted to support said belt rollers, a driving connection between one of said belt rollers and the machine, a bracket secured to another portion of said rock shaft having a counterweight slidably mounted thereon, a tensioned floating web guide roller, bearings for said floating web guide roller slidably mounted in guideways secured to the machine, equalizing means to provide an equalized sliding movement for each of said bearings comprising two sprocket chains and sprockets therefor, each chain having opposite ends thereof connected to one of each of said floating web guide roller bearings, and a link secured to one of said sprocket chains and to said counter-weight, whereby movement of the floating web guide roller will cause a corresponding movement by said link to rock the rocker arms and vary the pressure of the belt upon the web supply roll.
17. Web tensioning mechanism for controlling

the web feed to a printing machine, comprising a roller engaging a loop in the web, means for carrying the roller and biasing same to press against the web, a movable support, friction means movable with the support and engaging the peripheral surface of a web roll, a lever connected to move the support, and a weight movable on the lever and connected to the roller carrying means.

18. Web tensioning mechanism for controlling the web feed to a printing machine, comprising a roller engaging a loop in the web, means for carrying the roller and biasing same to press against the web, a movable support having a running belt thereon engaging the peripheral surface of a web roll, means for driving the belt at approximately the speed of the web, a lever connected to move the support, and a weight movable on the lever and connected to the roller carrying means.

19. In a web tensioning mechanism for controlling a web roll from which a web is being fed to a printing machine, a friction member supported to press against the peripheral surface of the web roll, a rocker member arranged to vary the pressure of said friction member when rocked, an arm secured to the rocker member, a weight slidable on the arm, a floating web guide roller running in a loop in the web, and connections between the roller and the weight, whereby movement of the roller in response to variation in the pull of the web will vary the pressure of the friction member against the roll.

20. In a web tensioning mechanism for controlling a web roll from which a web is fed to a printing machine, a movable support having a belt thereon engaging the peripheral surface of a web roll, a floating web guide roller running in a loop in the web, and a movable weight cooperating with said movable support and floating web guide roller to vary the pressure of the belt upon the web roll according to varying position of the floating web guide roller.

21. In a web tensioning mechanism for controlling a web roll from which a web is fed to a printing machine, a movable support having a belt thereon engaging the peripheral surface of a web roll, a floating web guide roller running in a loop in the web, means movable with said movable support and having a weight movable thereon, and connections between the floating web guide roller and weight, whereby movement of the floating roller in response to variation in the pull of the web will vary the pressure of the belt against the web roll.

22. In a web tensioning mechanism for controlling a web roll from which a web is being fed to a printing machine, a friction member supported to press against the peripheral surface of the web roll, a rocker member arranged to vary the pressure of said friction member when rocked, a movable weight cooperating with said rocker member, a web guide roller adapted to change its position according to variations in web tension, and connections between the web guide roller and the movable weight, whereby movement of the web guide roller in response to variation in the pull of the web will vary the pressure of the friction member against the roll.
